ELECTRIC TRANSLATION DEVICE MOUNT-
ING AND THE LIKE

Daniel K. Wright, Cleveland Heights, Ohio, and
Frederick H. Weston, Bridgeport, Conn., as-
signors to General Electric Company, a cor-
poration of New York

Application May 18, 1937, Serial No. 143,310

11 Claims. (Cl. 176—32)

The present invention relates to mountings for electric translation devices and the like of the type in which the co-operating plug is securely held in a socket against accidental displacement.

The object of our invention is to provide an improved construction and arrangement in mountings of this type, and, for a consideration of what we believe to be novel and our invention, attention is directed to the accompanying description and the claims appended thereto.

In the accompanying drawing, Fig. 1 is a side elevation in section along lines 1—1 of Fig. 2 of a socket embodying our invention with a plug inserted in the socket; Fig. 2 is an exploded top plan view of the socket with one of the locking plates removed; Fig. 3 is a sectional elevation taken on line 3—3 of Fig. 2; and Fig. 4 is an exploded view showing one of the contacts of the socket, the terminal which is connected to the contact, the prong which engages the contact, the locking plate which holds the prong in engagement with the contact, and a spring clip which may be snapped over the contact to prevent the decrease of contact pressure due to heating of the contacts.

Referring to the drawing, we have illustrated a socket for use with an electric lamp having a glass envelope 1 provided with a plug connector 30 which comprises a base 2 from which extend two prong terminals 3 rigidly fixed to the base by skirts 3a sealed thereto. Each of the prongs has a cylindrical contact-engaging portion 4 and a reduced portion 5, above a contact-engaging portion which provides a shoulder 6. The upper ends of the prongs are connected to rigid filament supporting rods 7 which serve as lead-in wires. The rods 7 locate the filament precisely with respect to the base. This type of plug connector is 40 used for heavy current lamps and the like, so that it is important that the prongs be held in firm engagement with the contacts of the socket.

The socket comprises a base 8 of porcelain or other suitable insulating material in the upper side of which are formed two pockets 9 and a central depression 9a for receiving the seal 9b of the lamp. In the pockets 9 are spring clip contacts 10, the open ends of which face in opposite directions, as shown in Fig. 2. The contacts may 50 be reinforced by spring clips 23 (see Fig. 4) which are snapped over the arms of the contacts. The spring clips prevent decrease in contact pressure due to heating of the arms of the contacts. The contacts are spot-welded to supports 11 which are secured to the base by screws 12

threaded into terminal plates 13 to which the line conductors are attached. Above each of the pockets 9 is a resilient metal locking plate 14 which is secured to the base by means of a bolt 15. The locking plates are provided with openings 15a through which the contact-engaging portions 4 of the prongs may be inserted and communicating narrow arcuate slots 16 into which the reduced portions 5 of the prongs enter when the plug is rotated relative to the socket 10 in a clockwise direction, as viewed in Fig. 2. The openings 15a are in axial alignment with the enlarged portions 23a of the spring clips 23, but are smaller in size. The edges of the slots 16 engage the shoulders 6 of the prongs and 15 prevent axial displacement of the prongs. As shown in Fig. 4, the locking plates are formed so that they are highest at their free ends adjacent the openings 15a. From the openings 15a the edges of the slots 16 have downwardly inclined portions 17 which engage the shoulders 6 on the prongs when the plug is rotated in clockwise direction after insertion in the socket and guide the reduced portions of the prongs into the narrow slots 16, and at the same time urge the 25 prongs toward the bottom of the socket. This resiliently forces the lower edge of the plug against shoulders 19 on the base and prevents any wobbling of the plug in the socket. This plug has a conical seating shoulder 10a which fits 30 in a complementary seating shoulder in the base 8 and centers the plug in the socket. This holds the lamp filament in fixed relation to the socket. At the end of the downwardly inclined portions 17 the locking plates have upwardly inclined portions 18 which engage the shoulder 6 and resist counter-clockwise rotation of the plug relative to the socket, which would tend to move the prongs of the plug out of engagement with the contacts. From one aspect, the inclined portions 40 17 and 18 provide a projection which locks the plug in the socket. The socket is mounted by a coupling 20 provided with arms 21 which are secured to the base by screws 22.

In the use of the socket, the prongs 3 of the 45 plug are inserted through the openings 15a in the locking plates 14. In this position the prongs are out of contact with the contacts 10 of the socket. In order to bring the prongs into engagement with the contacts, the plug is rotated in 50 a clockwise direction, as viewed in Fig. 2. The clockwise rotation of the plug causes the shoulders 6 on the prongs to engage the inclined portions 17 of the locking plates, causing the lower edge of the plug to be pulled downwardly into 55

tight engagement with the shoulders 19 on the base. Just prior to the complete engagement of the prongs with the contacts 10, the shoulders 6 of the prongs reach the upwardly inclined portions 18 of the locking plates. Since at this time a considerable twisting force is being exerted on the plug, the prongs of the plug are quickly moved into complete engagement with the contacts 10 due to the decreased resistance offered by the upwardly inclined portions 18. When the plug is to be removed from the socket, it is first turned in a counter-clockwise direction until the prongs enter the openings 15a. The inclined portions 18 of the locking plates resist the initial part of this movement, and as soon as the shoulders 6 reach the inclined portions 17, the prongs are quickly moved out of engagement with the contacts 10.

What we claim as new and desire to secure by Letters Patent of the United States is:

1. The combination of a translation-device base having an annular seating shoulder and contact terminal studs projecting from said base in the direction of the axis of said shoulder, and themselves provided with securing shoulders; a socket for said base having a seating shoulder for said base shoulder; resiliently yielding engagement means in said socket for coacting with said stud shoulders, to hold said base shoulder against said socket shoulder, engageable with the said stud shoulders by relative turning of base and socket after engagement of the base and socket shoulders, said engagement means having bottom projections in position for the stud shoulders to ride under them as base and socket are turned relative to one another; and contact means in the socket engageable with said studs by the relative turning of base and socket.
2. The combination of a translation-device base having an annular seating shoulder and contact terminal studs projecting from said base in the direction of the axis of said shoulder, and themselves provided with securing shoulders; and a socket for said base having a seating shoulder for said base shoulder; resilient members with keyhole slots for receiving said studs through their large portions and engaging the stud shoulders when the base and socket are turned relative to one another after insertion of the studs in the slots as aforesaid, said members having bottom projections in position for the stud shoulders to ride under them as the studs reach the limit of movement in the slots, and contact means in position to engage said studs as their shoulders pass under said projections.
3. The combination of a translation-device base having an annular seating shoulder and contact terminal studs projecting from said base in the direction of the axis of said shoulder, and themselves provided with securing shoulders; and a socket for said base having a seating shoulder for said base shoulder, resilient members with keyhole slots for receiving said studs through their large portions and coacting with the stud shoulders when the base and socket are turned to draw said base and socket shoulders against each other relative to one another after insertion of the studs in the slots aforesaid; and resiliently yielding contact means engageable with said studs, during the last of the turning movement, to lock base and socket against reverse turning relative to one another.
4. A socket having an annular seating shoulder for coacting with a corresponding annular body

or base shoulder, and also comprising resiliently yielding engagement means, for coacting with securing shoulders of contact terminal studs projecting from said base in the direction of the axis of the said base shoulder to hold said base shoulder against said socket shoulder, engageable with the said stud shoulders by relative turning of base and socket after engagement of the base and socket shoulders, said engagement means having bottom projections in position for the stud shoulders to ride under them as base and socket are turned relative to one another, and separate resiliently yielding contact means engageable with said studs by the relative turning of base and socket.

5. A socket for an electric translation device, said socket having an annular seating shoulder for coacting with a corresponding annular base shoulder of the device, resiliently yielding engagement means for coacting with securing shoulders of contact terminal studs projecting from said base in the direction of the axis of the said base shoulder to draw and hold said base shoulder firmly against said socket shoulder when base and socket are brought together and turned relative to one another, and separate resiliently yielding contact means in said socket for engaging said studs and thereby locking said base and socket against reverse turning relative to one another.

6. A socket for an electric translation device, said socket having an annular seating shoulder for coacting with a corresponding annular base shoulder of the device, resiliently yielding engagement means with keyhole slots for receiving through their large portions shouldered contact terminal studs projecting from said base in the direction of the axis of the said base shoulder, and engaging the stud shoulders when the base and socket are turned relative to one another after insertion of the studs in the slots as aforesaid, said engagement means having bottom projections in position with the stud shoulders to ride under them as the studs reach the limit of movement in the slots, and contact means in position to engage said studs as their shoulders pass under said projections.

7. A socket having an annular seating shoulder for coacting with a corresponding annular body or base shoulder, and also comprising resiliently yielding engagement means with keyhole slots for receiving through their large portions shouldered contact terminal studs projecting from said base in the direction of the axis of the said base shoulder, and coacting with the stud shoulders to draw said base and socket shoulders against each other when the base and socket are turned relative to one another after insertion of the studs in the slots as aforesaid, and resiliently yielding contact means engageable with said studs, by the relative turning of base and socket, after engagement of the said engagement means with the stud shoulders, to lock base and socket against reverse turning relative to one another.

8. A socket comprising a body portion having an annular seating shoulder, a plurality of resilient members having keyhole slots therein adapted to engage with prongs on a base and pull a shoulder on said base firmly against the said seating shoulder upon rotation of the base relative to the socket, and a plurality of contact clips located in alignment with said keyhole slots and adapted to engage said prongs upon the relative rotation of base and socket.

9. An electric socket for use with a plug hav-

ing a prong provided with a contact-engaging portion and a shoulder, comprising a base into which said prong may be inserted, a contact in said base arranged to engage said prong upon subsequent rotation of the plug relative to the base, and resilient locking means separate from said contact engaging said shoulder for holding the plug in the base, said locking means having an inclined portion for urging the plug 10 against the base during the rotation of the plug to the contact-engaging position.

10. An electric socket for use with a plug having a prong provided with a contact-engaging portion and a shoulder above said contact-engaging portion comprising a base, a resilient metal plate secured to said base having an opening through which said prong may be inserted and a communicating slot the edges of which engage said shoulder upon subsequent rotation of 15 the plug relative to the plate for holding the plug in the socket, and a contact for engaging said prong upon said rotation of the plug, said plate having an inclined portion engaging said

shoulder for urging the plug against the base during the rotation to the contact-engaging position.

11. An electric socket for use with a plug having a prong provided with a contact-engaging portion and a shoulder above said contact-engaging portion comprising a base, a resilient metal plate secured to said base having an opening through which said prong may be inserted and a communicating slot an edge of which engages said shoulder upon subsequent rotation of the plug relative to the plate for holding the plug in the socket, a contact for engaging said prong upon said rotation of the plug, said plate having an inclined portion engaging said shoulder for urging the plug against the base during the rotation to the contact-engaging position and having an oppositely inclined portion for opposing rotation of the plug away from the contact-engaging position. 20
